[57] CLAIM

The ornamental design for a fountain pen stand, as shown and described.

DESCRIPTION

FIG. 1 is a front elevational view of a fountain pen stand showing my new design;

FIG. 2 is a left side elevational view, the right side being a mirror image thereof;

FIG. 3 is a top plan view thereof; and,

FIG. 4 is a top, right rear perspective view thereof drawn to a reduced scale with respect to FIGS. 1 through 3.

The bottom of the article is plain and unornamented.
